UNITED STATES PATENT OFFICE.

ROBERT HUNTER, OF CHESANING, MICHIGAN.

DITCHING-MACHINE.

SPECIFICATION forming part of Letters Patent No. 451,558, dated May 5, 1891.

Application filed August 25, 1890. Serial No. 362,927. (No model.)

To all whom it may concern:

Be it known that I, ROBERT HUNTER, a citizen of the United States, residing at Chesaning, in the county of Saginaw and State of Michigan, have invented certain new and useful Improvements in Ditching-Machines; and I do hereby declare the following to be a full, clear, and exact description of the invention, such as will enable others skilled in the art to which it appertains to make and use the same.

My invention relates generally to ditching-machines, and particularly to improvements in the cutting, elevating, and discharging mechanisms by which trenches or ditches are formed and the loosened earth elevated and conveyed to one side thereof; and it consists in the peculiarities of construction and arrangement or combination of parts hereinabove fully disclosed in the description, drawings, and claims.

The objects of my invention are, first, to provide an improved plow or cutter for forming ditches; second, improved endless conveyers provided with buckets for elevating the cut or loosened earth and discharging the same at one side of said ditches; third, novel devices for effecting the tensioning of said endless conveyers and the cleaning of the buckets thereon after they have been emptied; fourth, novel scrapers for the removal of any earth that may adhere to the peripheries of the gage and traction-wheels; fifth, an improved scraper for leveling the earth in the bottoms of ditches, and, sixth, novel arrangements or combinations of these parts whereby a ditching-machine is produced which is effective in operation, capable of accomplishing the various results incident to this class of machines, simple in construction, and comparatively inexpensive to manufacture.

These objects I accomplish by the mechanism illustrated in the accompanying drawings, forming part of this specification, in which the same reference-numerals indicate the same or corresponding parts, and in which—

Figure 1 represents a side elevation of my improved machine with parts broken away and in dotted lines; Fig. 2, a rear elevation of a portion of the same, parts being shown in section on the line xx of Fig. 1; Fig. 3, a

perspective detail view of the plow or cutter and parts of its attachments; and Fig. 4, a rear detail view, enlarged, of the toothed scraper for the traction-wheel and the scraper for leveling the bottom of a ditch, both being mounted in rear of said wheel.

In the drawings, the numeral 1 indicates the plow or cutter, which, as more plainly represented in Fig. 3, is composed of the two vertically-arranged right and left side plates 2 and 3, the latter plate being formed with the vertical cutting-edge 4 for a portion of its height and with the downwardly-curved part 5, which extends forwardly from the lower end of said cutting-edge for the rest of its length, while the former plate is made with the rearwardly-inclined cutting-edge 6, which extends its full height and projects forwardly of the plane of the vertical cutting-edge 4 of the opposite side plate 3; also, said cutter is provided with the downwardly and forwardly curved plate or mold-board 7, which is slightly inclined toward or along its right edge, which extends rearwardly for some distance past the inclined cutting-edge 6 of the right side plate 2 and which abuts at the rear end of its left side against the lower end of the vertical cutting-edge 4 of the left side plate 3 and also with the angular plowshare 8, having the horizontal sharp point 9, the vertical knife or colter 10, and the cutting-edge 11, which is inclined to the right and rearwardly. This plowshare, having the features named, and the curved plate or mold-board 7 are removably connected by one or more screw-bolts 12; also, the vertical side plates 2 and 3 of the cutter are removably connected and firmly supported by the cross-braces 13, the ends of which are held by the bolts or screws 14 against the inner faces of said plates at the points indicated in Figs. 1 and 3.

Between the upper edges of the vertical side plates of the cutter is firmly bolted the enlarged rear end 15 of the horizontal beam 16, from which projects the upwardly and forwardly inclined beam 17, which, in connection with the downwardly and forwardly inclined and apertured plates 18, connected to the front ends of said beams, constitutes the draft-bar 19, to which power is applied through the adjustable clevis 20, whereby the

point of draft may be regulated to accord with the increasing depth of the ditch being formed.

Near the front end of the horizontal beam 16 is inserted the clamp-bolt 21, which passes through the slot 22, formed in the upper portion of the curved and adjustable support 23, in the lower end of which is journaled the guide or gage-wheel 24 for regulating the depth of cut of the cutter 1, as may be desired; also, just in rear of said support 23 the two-armed scraper 25 is pivoted to said beam 16, extends downwardly and forwardly, and rests at its lower closed end upon the periphery of said wheel 24 for clearing the same of any adhering earth. To the upper edges or inner surfaces of the side plates 2 and 3 of the cutter 1 is secured the upwardly and rearwardly inclined frame 26, in the upper end of which is journaled a sprocket wheel or roller 27, around and by which and a similar wheel or roller 28, which is mounted upon a shaft 29, journaled in and between said side plates near their lower edges is carried the endless conveyer 30, which is provided with the buckets 31, and so arranged at its forward or lower end as to receive the loosened earth from the mold-board 7. Thence it is carried upwardly and 30 discharged upon a similarly-constructed endless conveyer 32, which is carried within the chute 33, which is downwardly inclined and arranged at a right angle to and transversely beneath the upper end of said conveyer 30, 35 so as to deliver the earth at one side of the ditch as it is being formed. The buckets 31 of these endless conveyers are formed of the closely-arranged series of bent or right-angled plates 34, which are riveted or otherwise 40 suitably secured to the endless belts or chains 35, and so arranged that their horizontal bottoms will fit closely against their vertical sides or walls; also, their ends are arranged close to the sides of the frame 26 45 and the chute 33 for the purpose of preventing the discharge of their contents at those points.

To the rear or upper end of the frame 26 are secured the uprights 36, in the lower ends 50 of which is journaled the shaft 37 of the traction-wheel 38, on the left side of which is formed or secured the sprocket-wheel 39, around which passes the endless sprocket-chain 40, which extends upwardly and passes 55 over a similar wheel 41, which is attached to the inner end of a shaft 42, journaled in the upper portion of the left upright 36, as shown in Fig. 2. On the outer end of this shaft is secured the large gear-wheel 43, which meshes 60 with the small gear-wheel 44 on the outer end of the shaft 45 of the sprocket wheel or roller 27. The outer side or face of this small gear-wheel is provided with the beveled teeth 46, which mesh with the teeth of the bevel-pinion 47 on the front end of the shaft 48, which is journaled in the bracket 49 and in one side 65 of the chute 33, and upon which is mounted

the upper sprocket wheel or roller 50, which imparts downward movement to the upper surface of the transverse and downwardly-inclined endless conveyer 32, which, at the lower end of said chute, passes over the sprocket wheel or roller 51. The downward movement of this inclined endless conveyer is not only greatly assisted by the weight of the earth delivered into the buckets thereof, but also aids in drawing up and partly counter-balancing the weight of the earth in the buckets of the upwardly and rearwardly inclined endless conveyer, and in thus lessening the power required for operating the machine.

The tensioning of the chains or belts of the endless conveyers is provided for or accomplished by the rolls 52, which are journaled in the lower ends of the slotted hangers 53, 85 which are adjustably secured to the sides of the frame 26 and the chute 33 by the screw-bolts 54; also, similar hangers and adjusting devices are secured to said frame and chute, and in the lower ends of said hangers are 90 yieldingly journaled the shafts of the revolute brush-rolls 55, over which the buckets on the undersides of the endless conveyers pass, the result being that they are without injury thoroughly cleaned of any earth that may adhere thereto during their return to the cutter.

The uprights 36, in the lower ends of which the traction-wheel 38 is journaled, are strengthened or braced along their lower and middle portions by the bars 56 and the guide-handles 57, which are secured at their front ends to the inner surfaces of the vertical side plates 2 and 3 of the plow or cutter; also, to the lower end of the left one of these uprights is secured the horizontal bar 58, to the side of the rear end of which is pivoted the rearwardly and downwardly inclined scraper 59, which is forwardly curved for a portion of its length, and also provided with the transverse leveling extension 60 at its lower end for scraping or leveling the entire width of the bottom of the ditch, either after its completion or during its formation. At the point of its connection with the bar 58 it is formed with the slot 61 for permitting it to rise and pass over stones or other obstructions in the path of its movement; also, its pivotal connection with the rear end of the bar 58 is formed by the screw-bolt 62, by which it can be held in raised or vertical position when its use is not desired.

To the upper surface of the rear end of the bar 58 is secured the scraper 63, which is made of a plate of spring metal having a slight downward curve at its front end, which is formed with the teeth 64 for engaging the periphery of the traction-wheel 38 for permitting the pins or spuds 65 thereon to pass between them and for removing any earth that may adhere thereto or to said wheel. The rear end of this scraper, like that of the scraper 25 for the gage-wheel 24, is longitudinally slotted, as at 66, and adjustably held in place by the clamp bolt or screw 67, whereby

said scrapers may be held in or out of contact with their wheels—as, for instance, when the ditch is being cut in damp and clayey soils or in dry and sandy earths.

5 Having thus sufficiently described the construction and arrangement of the several parts of my invention to enable those skilled in the art to make and use the same and understand the operation and advantages thereof, what I claim as new is—

1. In a ditching-machine, a cutter provided with two removably-connected vertical side plates having cutting-edges on their front ends, a downwardly and forwardly curved and slightly-inclined mold-board, and an angular plowshare having a horizontal sharp point at its forward end, a vertical knife or colter, and a cutting-edge which is inclined rearwardly and to the right, substantially as described.

15 2. In a ditching-machine, the cutter 1, provided with the vertical right and left side plates 2 and 3, the latter being formed with the vertical cutting-edge 4 for a portion of its height and the former with a full-height rearwardly-inclined cutting-edge 6, which projects forwardly of said cutting-edge 4, the forwardly-curved mold-board 7, which is slightly inclined along its right edge, extended past said cutting-edge 6, and abutted against the lower end of said cutting-edge 4, the angular plowshare 8, having the sharp point 9, the vertical knife or colter 10, and the rearwardly-inclined cutting-edge 11, one or more screw-bolts 12 for removably connecting said mold-board and plowshare, and the cross-braces 13 and the bolts or screws 14 for removably connecting said side plates, substantially as described.

3. In a ditching-machine, an endless conveyor composed of an inclined frame, sprocket wheels or rollers, and an endless belt or chain provided with a series of closely-arranged buckets, which are formed of bent or right-angled plates and so arranged that their horizontal bottoms will fit closely against their vertical sides or walls and that their ends will be close to the sides of said frame, in combination with the slotted and adjustable hangers secured to the sides of said inclined frame and the spring-pressed or yielding brush-roll journaled in the lower ends of said hangers, substantially as described.

4. In a ditching-machine, an endless conveyor composed of an inclined frame, sprocket wheels or rollers, and an endless belt or chain provided with a series of closely-arranged buckets, which are formed of bent or right-angled plates and so arranged that their horizontal bottoms will fit closely against their vertical sides or walls and that their ends will be close to the sides of said frame, in combination with the slotted and adjustable hangers secured to the sides of said inclined frame, and the brush-roll yieldingly journaled in the lower ends of said hangers, substantially as described.

5. In a ditching-machine, an endless conveyor composed of an inclined frame, sprocket wheels or rollers, and an endless belt or chain provided with a series of closely-arranged buckets, which are formed of bent or right-angled plates and so arranged that their horizontal bottoms will fit closely against their vertical sides or walls and that their ends will be close to the sides of said frame, in combination with a similarly constructed and operated endless conveyor, which is geared to and operated from the conveyor first named and which is downwardly inclined and arranged at a right angle to and beneath the upper end of said first-named conveyor, and the yieldingly-journaled brush-rolls, one being arranged beneath each of said endless conveyors, substantially as and for the purpose described.

6. In a ditching-machine, an endless conveyor composed of an inclined frame, sprocket wheels or rollers, and an endless belt or chain provided with a series of closely-arranged buckets, which are formed of bent or right-angled plates and so arranged that their horizontal bottoms will fit closely against their vertical sides or walls and that their ends will be close to the sides of said frame, in combination with a similarly constructed and operated endless conveyor, which is geared to and operated from the conveyor first named and which is downwardly inclined and arranged at a right angle to and beneath the upper end of said first-named conveyor, the yieldingly-journaled brush-rolls, one being arranged beneath each of said endless conveyors, and a suitable plow or cutter arranged at the lower end of and communicating with said first-named conveyor, substantially as described.

7. In a ditching-machine, the combination, with a plow or cutter and two endless conveyors communicating therewith and arranged at right angles to each other, of means for imparting motion to said conveyors, the same comprising a traction-wheel having a sprocket-wheel on its side, a sprocket-chain connecting the same and another sprocket-wheel above, gearing intermediate of the same and the upper ends of said conveyors, and the yieldingly-journaled brush-rolls, one being arranged beneath each of said endless conveyors, substantially as described.

8. In a ditching-machine, the combination, with a plow or cutter and two endless conveyors communicating therewith and arranged at right angles to each other, of means for imparting motion to said conveyors, the same comprising a traction-wheel having a sprocket-wheel on its side, a sprocket-chain connecting the same and another sprocket-wheel above, gearing intermediate of the same and the upper ends of said conveyors, said gearing consisting of the shaft 42, the large gear-wheel 43, the small gear-wheel 44, having the beveled teeth 46 on its outer face

or side, the bevel-pinion 47, the shaft 48, and the yieldingly-journaled brush-rolls, one being arranged beneath each of said endless conveyers, substantially as described.

5 9. In a ditching-machine, the combination, with the horizontal beam 16, of the vertically-adjustable support 23, the gage-wheel 24, journaled in the lower end thereof, and the two-armed scraper 25, which is pivoted to said beam in rear of said support and adapted to rest at its lower closed end upon the periphery of said wheel, substantially as described.

10 10. In a ditching-machine, the combination, with the frame-work provided with the rearwardly-extending horizontal bar 58 and the screw-bolt 62, of the scraper 59, which is forwardly curved for a portion of its length, formed with the slot 61 in its upper end, and provided with the transverse leveling-exten-

15 sion 60, substantially as and for the purpose 20 described.

11. In a ditching-machine, the combination, with the frame-work provided with the rearwardly-extending horizontal bar 58 and the traction-wheel 38, journaled in said frame-work, and provided with the pins or spuds 65 on its periphery, of the spring-metal scraper 63, which is formed with a slight downward curve and the teeth 64 at its front end and with the slot 66 at its rear end, and the clamp 30 bolt or screw 67, substantially as and for the purpose described.

In testimony whereof I affix my signature in presence of two witnesses.

ROBERT HUNTER.
